FIBER PROCESSING CABINET

Cecil S. Wise, Dallas, N.C. (½ Fiber Controls Corp.,
P.O. Box 1358, Gastonia, N.C. 28052)

Filed Mar. 3, 1966, Ser. No. 1,276

Term of patent 14 years

(Cl. D55—1)

Fig. 1

FIG. 2

FIG. 3

FIGURE 1 is a perspective view of one side and top of my new design for fiber processing cabinet;

FIGURE 2 is a perspective view from the opposite side of the fiber processing cabinet shown in FIGURE 1; and

FIGURE 3 is a top plan view of the fiber processing cabinet shown in FIGURES 1 and 2.

The broken lines are for illustrative purposes only.
I claim:

The ornamental design for a fiber processing cabinet, substantially as shown and described.
